UNITED STATES PATENT OFFICE

2,442,101

EXPANSIBLE CHAMBER MOTOR WITH
FLUID ACTUATED CAM CONTROLLED
INLET AND EXHAUST VALVES

William H. G. Stone, Tacoma, Wash.

Application January 19, 1945, Serial No. 573,538

7 Claims. (Cl. 121—115)

1

This invention relates to a motor to be operated from any desired fluid under pressure, such as steam, compressed air, etc., and has for its principal object the provision of a simple and highly efficient motor mechanism in which the valves will be pressure-operated so that they will operate in consequence of the pressure cycles of the motor without requiring mechanical operation, so as to eliminate the usual cam shafts, drive gears, rocker arms, etc., with their attendant wear, noise, and absorption of power.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a cross section through the improved pressure motor; and

Fig. 2 is a detail section taken on the line 2—2, Fig. 1.

The improved motor consists of a cylinder block 10 having a plurality of pressure cylinders formed therein. As illustrated, the block is formed with two cylinders 11 and 12. A crank case 13 is bolted to the engine block 10 by means of suitable crank case bolts 14.

A piston 15 is mounted in each of the cylinders 10 and 11 from each of which a piston rod 16 extends. The piston rods 16 operate through guide members 17 and terminate in connecting links 18. The links 18 are connected with the opposite extremities of a rocker arm 19, which is keyed or otherwise secured on a crank shaft 20.

Thus, reciprocation of the pistons 15 in the cylinders will impart an oscillating motion to the crank shaft 20.

The pistons are reciprocated by means of fluid pressure entering through an intake 21, which feeds an intake passage 22 leading to an intake valve 23 in each cylinder. The pressure is relieved from the cylinders by means of exhaust valves 24, there being one exhaust valve 24 in each cylinder. The exhaust valves 24 exhaust to an exhaust passage 25 leading to an exhaust manifold 26.

The valves 23 and 24 are operated by means of a valve cam bar 27, which is reciprocally mounted in a valve bar housing 28 across the head of the cylinders 11 and 12. The cam bar

2

27 is provided with an elongated intake cam 29 and two exhaust cams 30. The stems of the valves 23 and 24 terminate in box-like cross heads 31 through all of which the cam bar 27 passes. Each of the cross heads 31 is provided with a bearing boss 32. The bosses 32 bear against the respective cams 29 and 30.

The exhaust valves 24 are constantly urged upwardly toward their seats by means of exhaust valve springs 33, and the intake valves are constantly urged downwardly toward their seats by means of intake valve springs 34.

The cams on the cam bar 27 are so positioned that, when the bar is moved axially in one direction, it will open the intake valve 23 of cylinder 12 and the exhaust valve 24 of cylinder 11 and, when moved in the other direction, it will open the exhaust valve 24 of cylinder 12 and the intake valve 23 of cylinder 11. The cam bar 27 is moved axially by means of control pistons 35 secured on the two extremities thereof.

The pistons 35 operate in operating cylinders 36 to which fluid under pressure is conducted by means of pressure conduits 37, which communicate through the walls of the respective cylinders 11 and 12 immediately above the lowermost position of the pistons 15 therein.

Operation

30 Let us assume that the pistons 15 are in the positions illustrated in Fig. 1, and that fluid under pressure is flowing into the intake 21. This fluid will flow through the open valve 23 of the cylinder 12, forcing the piston 15 therein downwardly. This downward movement will tilt the rocker arm 19 so as to force the piston 15 upwardly in cylinder 11. This will exhaust the fluid from the latter cylinder through the open valve 24 therein.

40 This movement or cycle will continue until the piston 15 of cylinder 12 passes below the opening of the pressure pipe 37 therein. When this occurs, fluid under pressure will flow to the right hand operating cylinder 35, forcing the piston 35 therein to the left. This shifts the cam bar to cause the right hand cam 30 to open the exhaust valve 24 of cylinder 12 and to cause the cam 29 to open the intake valve 23 of cylinder 11. The pressure is thereby conducted to cylinder 11 to force the piston 15 downward therein until it admits pressure through the left conduit 37 to the left operating cylinder 36 to return the valve bar to its original position.

While only two cylinders have been illustrated, additional banks of two cylinders each can

be positioned along the crank shaft 20 to provide the desired power.

While the invention has been described as a motor, the same construction could be used on an air compressor or pump, if desired.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. A pressure motor comprising: a pair of cylinders; a power piston reciprocally mounted in each of said cylinders; an intake valve for admitting fluid under pressure to each cylinder; an exhaust valve for discharging fluid from each cylinder; a reciprocally mounted cam bar; cams on said bar for operating said valves; an operating piston on said cam bar; an operating cylinder surrounding said piston; means for admitting fluid under pressure to said operating cylinder when one of the power pistons has reached a pre-determined point in its cylinder to cause said operating piston to move said cam bar in one direction; and means for returning said cam bar in the other direction when said power piston has reached a different point in its cylinder.

2. A pressure-operated motor comprising: a crank shaft; a pair of power cylinders; a power piston in each of said cylinders; means connecting said pistons to said crank shaft to impart movement to the latter; an intake valve in each power cylinder; an exhaust valve in each power cylinder; a slidably mounted valve bar; cams on said bar positioned to alternately open and close the valves of each cylinder; pressure operated means for reciprocating said bar; and a valve port in each cylinder over which the piston in that cylinder passes, said ports being connected to said pressure operated means to control the latter in consequence of the position of said power pistons in said power cylinders.

3. A pressure-operated motor comprising: a crank shaft; a pair of power cylinders; a power piston in each of said cylinders; means connecting said pistons to said crank shaft to impart movement to the latter; an intake valve in each power cylinder; an exhaust valve in each power cylinder; a slidably mounted valve bar; cams on said bar positioned to alternately open and close the valves of each cylinder; pressure-operated means for reciprocating said cam bar; and means for admitting fluid under pressure to said pressure-operated means from the power cylinders when the pistons in the latter have reached a pre-determined point therein to move said bar in one direction; and means controlled by said power pistons for moving said bar in the other direction.

4. A pressure-operated motor comprising: a crank shaft; a pair of power cylinders; a power piston in each of said cylinders; means connecting said pistons to said crank shaft to impart movement to the latter; an intake valve in each power cylinder; an exhaust valve in each power cylinder; a slidably mounted valve bar; cams on said bar positioned to alternately open and close the valves of each cylinder; a pair of operating pistons connected with said cam bar; an operating cylinder surrounding each of said latter pistons; a conduit extending from each of the operating cylinders through the wall of one of the power cylinders so as to be uncovered by the power piston when the latter approaches the extremity

of its stroke so that fluid under pressure will flow from ahead of the piston of one of the power cylinders to an operating cylinder to reciprocate the cam bar in one direction and from the other operating cylinder to a point behind the piston in the other power cylinder to exhaust the fluid therefrom whenever one of the power pistons approaches its extreme position.

5. A pressure-operated motor comprising: a crank shaft; a pair of power cylinders; a power piston in each of said cylinders; means connecting said pistons to said crank shaft to impart movement to the latter; an intake valve in each power cylinder; an exhaust valve in each power cylinder; a stem projecting from each valve; a cross head on each stem; a cam bar extending through all of said cross heads; intake cams on said cam bar positioned to contact the cross heads of the intake valves; exhaust cams on said cam bar positioned to contact the cross heads on the exhaust valves; and pressure-operated means for reciprocating said cam bar in consequence of the position of the power pistons in the power cylinders.

6. A pressure-operated motor comprising: a crank shaft; a pair of power cylinders; a power piston in each of said cylinders; means connecting said pistons to said crank shaft to impart movement to the latter; an intake valve in each power cylinder; an exhaust valve in each power cylinder; a stem projecting from each valve; a cross head on each stem; a cam bar extending through all of said cross heads; intake cams on said cam bar positioned to contact the cross heads of the intake valves; exhaust cams on said cam bar positioned to contact the cross heads on the exhaust valves; a cam operating cylinder; a piston in said latter cylinder connected with said cam bar; a conduit from one of said operating cylinders to said power cylinder, there being a port in the latter controlling the former so the pressure will be admitted to said operating cylinder when the power piston reaches a pre-determined position in that power cylinder to force said cam bar in one direction; and means for returning said cam bar in the other direction at a predetermined position of said power pistons.

7. A pressure-operated motor comprising: a crank shaft; a pair of power cylinders; a power piston in each of said cylinders; means connecting said pistons to said crank shaft to impart movement to the latter; an intake valve in each power cylinder; an exhaust valve in each power cylinder; a stem projecting from each valve; a cross head on each stem; a longitudinally movable cam bar extending through all of the cross heads; cams on said bar arranged to contact the cross heads so as to alternately open and close the intake and exhaust valves of the two cylinders as said bar is reciprocated back and forth; a piston on each extremity of said bar; an operating cylinder enclosing each piston; and a port in each cylinder positioned to be uncovered by the front pressure face of the piston therein as the latter approaches the extremity of its power stroke, and to be uncovered by the back no-pressure side of the piston as the latter enters on its exhaust stroke so that fluid under pressure will be alternately admitted from each power cylinder to each operating cylinder to reciprocate said bar in unison with the operation of said power cylinders.
